UNITED STATES PATENT OFFICE

SUSANNA COCROFT, OF NEW YORK, N. Y.

HAIR-WAVING DEVICE

Application filed July 18, 1930. Serial No. 468,814.

My invention relates to hair waving devices which are adapted for use with electricity, and it is addressed particularly to the simplification of the means required for imparting to the hair the wavy appearance which is known as a "permanent" wave.

The main object of the invention is to enable a person to give to her hair a permanent wave without the aid of anyone, and to impress the said wave upon the hair in a single operation.

Another object of the invention is to make it possible for one to put a wave into her newly grown hair without affecting the remainder of the wave-impressed hair, so that, as a fresh growth reaches the requisite length, a new wave near to the scalp is added, thus keeping hair permanently waved without subjecting that already waved to another waving process.

Another object of the invention is the provision of means which are so combined that they will enable an entire head of hair to be waved in about an hour.

Another object of the invention is the production of a hair waver which, while of great efficiency, is simple in operation, durable in construction, and provides a practical, safe and inexpensive device for home use.

Other objects, and advantages will be evident from the following description, taken in connection with the drawings forming part hereof, corresponding parts in said drawings being designated by similar numerals of reference, in which

Fig. 1 is a perspective view of my improved device;

Fig. 2 is a front elevation of the same;

Fig. 3 is a view similar to Fig. 2 showing certain of the members in section;

Fig. 4 is a longitudinal section of the prongs or jaws in closed position.

Fig. 5 is a transverse section substantially through the center of the device showing the heating element in normal position;

Fig. 6 is a similar view with the heating element 2 screwed down into operative position;

Fig. 7 is a view from the right in Fig. 4

with the upper and lower jaws separated; and

Fig. 8 is a view from the left of Fig. 4 showing the elongated opening indicated in section in the former figure.

The art of permanent hair waving as generally practised at the present time consists broadly of three steps, (1) softening the hair with a suitable liquid, (2) steaming it with the steam emanating from said liquid, and (3) stretching the cells of the hair while it is being steamed so that the cells will be elongated and cause the hair to retain the curls given to it while thus stretched under the steam. Heretofore permanent wave devices have accomplished this result by winding the hair around small rods and then tightening it as the steam is applied. As a consequence the hair naturally comes out in the form of round curls which, by various means, must then be set and pressed to cause them to assume the wave effect desired.

By the present invention, however, the operation is greatly simplified. The hair is placed in the waver flat, and by the method and means hereinafter described, comes out in the form of an undulating wave instead of a curl, and retains the wave imparted to it even after repeated washings.

This result is accomplished by my novel device which is shown in perspective in Fig. 1 of the drawings. It is made up of a hollow handle 1. Attached to it and partly extending into the same is a hollow metallic curved tube 2 for the reception of a heating unit. The tube 2 having a curvature to conform with the head is equipped with an oval bushing member of metal 3. Encircling the tube 2 is a substantially oblong housing 5 which is open at the front and is provided with an elongated opening 6 at the back, the length of said opening being larger than the circumference of the tube 2. The member 5 is held in position on tube 2 by means of its downwardly projecting wall 7 surrounding the opening 6 being caught and held between the bushing 3 and the adjacent end of the handle. It is obvious that this construction permits the handle 1 and tube 2 with its attached parts

to be moved as a unit within the limits prescribed by opening 6.

Pivottally attached to the member 5 are metallic prongs or jaws 8 and 9 shaped to conform to the contour of the head. These are substantially U-shaped or semicircular in cross-section, and are provided with flanged ends 10 and 11 which in closed position overlap as shown in Fig. 4. Jaw 8 near its outer 10 end is equipped with a knobbed locking screw 12 to engage with socket 13, and about midway its length the said jaw has a similar knobbed pressure screw 14 for the purpose hereinafter described. For the purpose of 15 protecting the scalp from the heat of the waver a strip of non-heat-conducting material 15 is attached to the lower surface of the jaw 9. Both jaws 8 and 9 are provided with small grooves 16 along the length of their 20 edges to accommodate pieces or strips of rubber or other suitable material 17.

A removable jacket or bag of woven asbestos cloth or any other suitable material adapted to be placed over tube 2 is indicated 25 by 18, and 19 designates a perforated metal protector in the form of the cylinder closed at one end adapted to be slipped over the said jacket.

In the ensuing description of my invention 30 in practise, the work of the individual elements and their co-operation in the production of the finished result will be made clear.

Assuming that a heating unit has been placed in tube 2 and connected in the usual 35 way, as by cord 20, to a source of electricity, and that the user desires to give herself a permanent wave, the hair is parted and draped on each side of the head. The waver is held firmly in the hand by means of handle 1, the 40 tube 2 bearing its removable cloth jacket 18 (which has been previous moistened with a suitable permanent wave liquid), and over that the perforated metallic cylinder 19, being raised somewhat and held against the inside 45 of the top of jaw 8. A section of the hair is then laid smoothly flat over the lower jaw 9, the scalp-protecting member 15 contacting with the head, after which the upper jaw is closed and screwed into place by means of 50 locking screw 12 and socket 13. The members are now in the position illustrated in Fig. 5, the jaws positively forming a closed tube, and the enclosed portion of the hair being stretched and held straight across and between the upper and lower jaws, where it is 55 held practically immovable between the strips of rubber fastened to the edges of jaws 8 and 9. The screw 14 is next operated to press the tube with its wet jacket and perforated protector down upon the hair, as shown in Fig. 6, but not until steam has been produced by 60 heat on the wet jacket. The hair cells are thus stretched or elongated as the hair is pressed into the form of a wave, which elongation is necessary to make a wave perma-

nent. As stated, however, the hair is not stretched until it is being subjected to the steam generated by the liquid applied to the wet jacket. The operation is then repeated with another section of the hair until the desired wave has been imparted to the entire head of hair.

While in the embodiment of my invention herein shown and described I employ a locking screw to hold the jaws in close engagement 75 with each other, it is obvious that other means may be utilized for the purpose accomplished by said screw, which is to so securely clamp the said jaws together that the hair placed therebetween is held practically immovable 80 between them or the strips of rubber fastened to their edges. It is clear, too, that any suitable material may be employed in place of the rubber strips for assisting or reinforcing the jaws in maintaining a fixed grip on said hair. 85

One of the advantages of my waver is that because of its curved construction it conforms with either the side or back of the head, thus enabling a short or a long wave to be placed 90 wherever desired and at any angle.

Another advantage is the ease with which the chemical needed in permanent waving is put to use through the saturation of an absorbent jacket or bag quickly attached to and removed from the heating element 2.

While I have described the preferred form 95 of my invention, I do not wish to be limited strictly thereto as various changes may be made therein without departing from the spirit of the invention or the scope of the 100 appended claims.

What I claim as new and desire to secure by Letters Patent is:

1. Hair waving means including in combination a handle to which is rigidly fixed a tube for the reception of a heating element, a bag of absorbent heat-resisting material adapted to be removably attached to said tube, two prongs separately pivoted attached to said handle and adapted to enclose said tube, means for positively locking the prongs together, and screw pressure means mounted in one of the prongs whereby hair laid over the other prong may be positively locked between the said two prongs, and, on the operation 105 of the screw pressure means, subjected to the pressure of the said tube and the material carried thereby, substantially as and for the purpose described.

2. Hair waving means including in combination a handle to which is rigidly fixed a tube for the reception of a heating element, two separately pivoted prongs U-shape in cross section attached to said handle, one prong equipped with independently operable 110 screw locking and screw pressure means and the other with a socket to receive the locking screw, and a bag of absorbent heat resisting material adapted to be removably attached to said tube, whereby hair laid over the prong 115

equipped with a socket is, on the operation of the locking screw, positively held between it and the other prong for the purpose herein described, after which the pressure screw is operated to force the tube and material carried thereby into contact with said hair to subject the same to the necessary stretching pressure, substantially as set forth.

3. Hair waving means of the character described including a handle to which is rigidly fixed a heating element tube, two separately pivoted prongs U-shape in cross section attached to said handle, one prong equipped with separate locking screw and pressure screw means and the other with a socket to receive the locking screw, a jacket of absorbent material adapted to be removably attached to said tube, and a perforated metallic cylinder adapted to be removably attached to said jacket of absorbent material, whereby hair laid over the prong equipped with a socket is, on the operation of the locking screw, positively held between it and the other prong for the purpose herein described, after which the pressure screw is operated to force the screw and members carried thereby into contact with said hair to subject the same to the necessary stretching pressure, substantially as set forth.

4. Hair waving means comprising a heating element tube and two separately pivoted prongs mounted thereon and adapted to enclose said tube, the upper of the said prongs having a locking screw co-operating with a socket on the lower prong, said upper prong also equipped with a pressure screw, whereby on the operation of the locking screw a portion of hair engaged between the two prongs is held firmly therebetween, the pressure screw being subsequently operated to force the heating element tube into close contact with the said hair, substantially as and for the purpose set forth.

5. Hair waving means including a waver comprising a heating element member, two independently operable prongs mounted thereon, U-shape in cross section and adapted to enclose said heating element member, and having flanged ends which in closed position overlap, the said tube and prongs being curved to conform to the human head, one of said prongs equipped with screw-locking means to co-operate with a socket on the other prong, and the first-named prong being also equipped with screw pressure means, substantially as and for the purpose set forth.

6. Hair waving means of the character described comprising a waver consisting of a handle, a heating element tube extending therein and a housing connected therewith, two prongs separately pivoted to said housing having flanged ends which overlap and being adapted to enclose said tube, the said tube and prongs being curved to conform to the human head, the upper prong equipped with inde-

pendently operable locking screw and pressure screw means, a removable bag fitting over the said tube and a removable perforated cylinder fitting over said bag, and the contacting edges of the prongs being provided with strips of flexible material, substantially as and for the purpose described.

7. In a hair waving device, the combination of two prongs, a tube cooperating therewith, a heating element within said tube, and an absorbent covering for said tube.

8. In a hair waving device the combination of a handle, a heating element, a tube mounted on said handle and adapted to receive said heating element, and a bag covering of absorbent material adapted to be slipped onto said tube.

9. In a hair waving device, the combination of a handle, a heating element, a tube mounted on said handle and adapted to receive said heating element, a bag of absorbent material adapted to be slipped onto said tube, and a perforated cylinder adapted to enclose said bag when in assembled position.

10. In a hair waving device, the combination of a pair of pivotally connected prongs shaped to form a closed compartment when in the closed position, a tubular heating element arranged between said prongs and an absorbent covering for said heating element.

11. In a hair waving device, the combination of a pair of pivotally connected prongs shaped to form a closed compartment when in the closed position, a heating element arranged between said prongs, an absorbent covering for said heating element, and a perforated cylinder adapted to be slipped over said covered heating element.

In testimony whereof, I have signed my name to this specification.

SUSANNA COCROFT.
